UNITED STATES PATENT OFFICE.

MILTON D. MESEROLE, OF MILFORD, CONNECTICUT, ASSIGNOR TO THE HAYES-MESEROLE MFG. CO., INC., OF MILFORD, CONNECTICUT, A CORPORATION.

HAIR CURLER.

Application filed October 22, 1923. Serial No. 669,991.

To all whom it may concern:

Be it known that I, MILTON D. MESEROLE, a citizen of the United States, residing at Milford, in the county of New Haven and State of Connecticut, have invented a new and useful Improvement in Hair Curlers; and I do hereby declare the following, when taken in connection with the accompanying drawings and the characters of reference 5 marked thereon, to be a full, clear, and exact description of the same, and which said drawings constitute part of this application, and represent, in—

Fig. 1 a plan view of a hair curler constructed in accordance with my invention, and shown in position as having gripped the ends of a lock of hair.

Fig. 2 a side view with the curler in its final closed position.

Fig. 3 a plan view of a curler of the preferred form.

Figs. 4, 5 and 6 plan views of modified forms of the same.

This invention relates to improvement in hair curlers, and particularly to curlers which are formed from covered wire, so as to be flexible. In the use of the curlers, the ends of a lock of hair are held by the fingers at the center of the curler, then the

curler turned so as to roll the hair around the curler, after which the ends are folded inward, to hold the hair in place. In curling bobbed hair, difficulty is experienced in holding the end of a lock and the object

of this invention is to provide a flexible curler with a tongue, by which the end of a lock of hair may be held so as to leave both hands free to roll the curler, and the invention consists in the construction as herein-

after described and particularly recited in the claims. In one form of my invention, as shown in Figs. 1, 2 and 3 of the drawings, the curler is formed from a single piece of flexible material, folded so as to form three

members 10, 11 and 12. These members are secured together at the center by a clip 13 of metal or other suitable material. This provides a flexible curler with two tongues 14 and 15. In use the ends of a lock of hair

50 are placed over the central part of the

curler and the tongue 15 folded over onto it, as shown in Figs. 1 and 2 of the drawings, so as to firmly hold the lock of hair. If desired, the tongue 14 may also be folded onto the lock, so as to assist in holding it. The 55 curler is then turned so as to wind the hair around it in the usual way, and then the looped ends of the wire are folded inward, as shown in Fig. 2 of the drawings.

Instead of providing the tongue 14, this 60 end of the wire may be cut off, as shown in Fig. 4 of the drawings, leaving only a single tongue 15, or, instead of folding the wire, as shown in Figs. 3 and 4 of the drawings, so that the tongue 15 is arranged centrally 65 between the members 10 and 12, the wire may be bent into S-shape, as shown in Fig. 5 of the drawings, so as to provide two tongues 16 and 17; or, instead of forming the device from a single piece of wire, it 70 may be formed from three strands of wire 18, 19 and 20, as shown in Fig. 6 of the drawings. In any case, the same central loop 13 will be employed for holding them together, and in each case, a tongue is provided for primarily gripping a lock of hair. When the lock is gripped, both hands are 75 free to manipulate the curler, which is then manipulated in the usual manner.

I claim:

1. A flexible hair curler, comprising three flexible members, means for connecting the members together near the center, one of said members forming a tongue adapted to be turned over the ends of a lock of hair 85 placed over the curler.

2. A flexible hair curler, formed from a single piece of wire, bent to form three members of substantially the same length, a clip connecting the three members, whereby a 90 tongue is formed and adapted to be turned over the ends of a lock of hair placed over the curler.

In testimony whereof, I have signed this specification in the presence of two subscribing witnesses.

MILTON D. MESEROLE.

Witnesses:

FREDERIC C. EARLE,

MALCOLM P. NICHOLS.
